UNITED STATES PATENT OFFICE.

ALBRECHT BRINNHÄUSER, OF NUREMBERG, GERMANY.

MACHINE FOR SLICING MEAT, SAUSAGES, AND OTHER EDIBLES.

No. 853,294.

Specification of Letters Patent.

Patented May 14, 1907.

Application filed May 16, 1904. Serial No. 208,321.

To all whom it may concern:

Be it known that I, ALBRECHT BRINNHÄUSER, residing at and whose post-office address is No. 91 Sulzbacherstrasse, of Nuremberg, Bavaria, in the Empire of Germany, manufacturer, have invented certain new and useful Improvements in Machines for Slicing Meat, Sausages, and other Edibles; and I do hereby declare the following to be a full, clear, and exact description of the invention, such as will enable others skilled in the art to which it appertains to make and use the same.

This invention relates to a new or improved machine for cutting or slicing meat and similar edibles, more particularly ham and sausages.

The machine has the advantages of simplicity, reliability and cheapness, and of being easy to manipulate.

One form of the invention is illustrated in the annexed drawing, in which

Figure 1 is a side view of the machine in section on line C—D of Fig. 2, and Fig. 2 a section on the line A—B of Fig. 1, Fig. 3 presents a detail.

The machine essentially comprises the frame *a*, the carriage or slide *b* and the rotary knife *c*. It is operated by means of the hand wheel *d*, the shaft *e* of which has bearings in the frame *a*. To the rear-end of the shaft *e* is fixed the bevel-wheel *f* which meshes with the bevel-wheel *g* on the shaft *h* mounted in the frame. To the outer end of the shaft *h* (Fig. 2) is fixed the wheel *i* connected by means of a chain or the like with the wheel *k*, which it is adapted to drive. The wheel *k* is fixed to the axle *l* of the knife *c*, said axle *l* having bearing in an arm *m* fixed to the frame.

The knife *c* comprises a wheel-like support *n*, the circumference of which is beveled to receive the blade *o*, which is screwed thereto. The said blade *o* consists of several segments, each of which is separately removable and replaceable so that in case of injury to one part of the blade the entire blade need not be replaced. An integral disk or ring can, however, be screwed to the support *n* instead of the segments referred to. In either case the blade must be inclined with the regard to the plane in which the cut is to take place, in order to facilitate its action.

To the bevel wheel *g* is fixed a plate *p* which is connected to an arm *r* by means of a pivot *q*. The said arm *r* is pivoted at *s* to a

lever *t* fulcrumed at *u* on the bed-plate of the machine. To the upper end of the lever *t* the arm *w* is pivoted at *v*, said arm being pivoted at *x* to a projection *y*, which is fixed to the slide *b*. By this means the latter can be reciprocated parallelly to the plane of cutting. The slide *b* is provided with the dovetail guides *z* in which the meat plate *1* is movable. On this plate the meat or the like to be cut is placed, an engaging member or vertical plate *2* and the rack *3* being arranged on said plate *1* for that purpose. The plate *2* is provided with two rows of holes *4* which the hooks *5* of a pronged meat bar *6* engage. The latter is placed on the meat and holds it against the plate *1* by means of teeth, prongs or the like. The handle *7* is movable on the plate *8*, being provided with slots *6* engaging the pins *9* fixed to the plate. One end of the said handle is provided with the bent nose *10* which is adapted to engage between the teeth *11* of the rack *3*. By displacement of the handle *7* the said nose can be moved into and out of engagement with the said rack. The hooks *5* can be inserted into the holes *4* as required.

To the underside of the movable plate *1* is fixed a projection *12*, to which a lever *13* is pivoted. The curved part *14* of the latter is screw-threaded on its inside, so that said part *14* forms, as it were, one half of a nut, which engages the screw *15* mounted in bearings *16* on the under part of the slide *b* (Fig. 2). To the screw *15* is fixed a ratchet wheel *17*, which is so held by a spring *18* that it can only revolve toward the right, as seen in Fig. 3. Below this ratchet wheel *17* is arranged a slide *19* adapted to be moved by means of a rod *20* and to be fixed in the desired position by means of notches or holes *21* therein and the pin *22* fixed to the frame *a* of the machine. The rod *20* is held in position by means of a spring *23*. To the slide *19* is fixed a guide frame *24*, provided with a slot into which engages a pin *25* fixed to the machine frame. The slide *19* is provided with a row of spring mounted rack teeth *26*, each of which is held in an elevated position by a spring *27*. These teeth are movable and can be depressed by overcoming the pressure of the springs *27*. The upward movement of the teeth *26* is limited by the steps or heads *28*. The lever *13* is connected with a rod *29* guided in arms *30* fixed to the vertical plate *2*. At the upper end of the rod *29* is arranged a spring *31*, which bears against one

of said arms 30 and against a knob 32 at the end of the rod 29, so that the said spring tends to move the latter upward. The rod 29 is provided with a recess 33 and is guided 5 in an aperture 34 in a bell-crank lever 35. The latter is pivoted at 36 to the plate 2 and is so operated by a spring 37 that it always engages into the recess 33 on the rod 29. The free end to the lever 35 is provided with 10 a vertical finger 38 which in its end position abuts against a pin 39 so as to operate the lever 36.

The action of the machine is as follows: The parts are at the beginning in the positions indicated by dotted lines. The slide 15 *b* which is adapted to be reciprocated in the guides 40 on the frame *a*, is at this stage at the end of the guides nearest the wheel *d*. If the latter is thereupon operated the shaft 20 *c* is revolved and rotates the shaft *h* by means of the wheels *f* and *g*. The rotation is transmitted from the shaft *h* to the axle *l* of the knife by means of the wheels *i* and *k*, so that the knife is revolved. During the rotation of 25 the wheel *g* the plate *p* acts as a crank arm and operates the arm *r* in such a manner that the lever *t* is caused to oscillate about the pivot *u*. The upper end of the said lever *t* moves the rod *w*, by which means the carriage *b* is caused to reciprocate in the guides 30 40. The rotation of the wheel *d* thus causes the knife to be revolved and the slide *b* to be reciprocated. With the slide the parts 1 to 39 thereon are, of course, also reciprocated. 35 The edible to be cut, for instance a sausage, is placed on the plate 1 and covered by means of the plate 6, the hooks 5 being inserted into suitable holes 4, according to the size of the sausage. The handle 7 is then pushed 40 over to the right till the projection 10 engages one of the teeth 11 of the rack 3. By this means the sausage is held firmly on the plate 1. It is obvious that when the slide moves toward the knife a slice will be cut off 45 the sausage. In order to cut the next slice the sausage will have to be moved in a direction perpendicular to the plane of the knife. This is effected in the following manner. While the slide *b* is moving in its guides 40 50 the ratchet wheel 17 on the screw 15 slides over the slide 19. According to the position of the latter, one or more of the teeth 26 engages or engage the ratchet wheel and rotate the said wheel through the space of the corresponding number of teeth. The screw 15 is revolved with the wheel 17, and since the screw threaded part 14 of the lever 13 is in engagement with the said screw 15, the said lever 13 is displaced on the latter. The lever 55 60 13 is connected to the projection 12 of the plate 1 and to the rod 29 arranged in bearings 30 on the plate 2, so that the plate 1 is moved in the guides *z* and with it the plate 2, rods 29 and lever 36 are moved perpendicularly to the plane of the knife. The extent of 65

this displacement depends to the extent of the rotation of the screw 15, that is to say, on the number of teeth 26 which engage the ratchet wheel 17. The displacement of the plate 1 can thus be regulated by adjusting the 70 slide by hand, by means of the rod 20. The sausage being held fast on the plate 1, the displacement of the latter causes the former to be moved toward the cutting plane, and the thickness of the slices to be cut can be 75 regulated in the manner described. When the plate 1 has advanced farthest toward the knife the vertical finger 38 of the lever 35 abuts against the pin 39 on the frame *a* and is by this means pushed back in order to 80 rotate the lever 35 against the pressure of the spring 37 (from left to right, Fig. 2) so that said lever 35 is disengaged from the recess 33 in the rod 29. The said rod 29 is thereupon moved upward by the spring 31 into 85 the position indicated in Fig. 1 by dotted lines, and moves with it the lever 13, which is also moved into the position indicated by dotted lines in Fig. 1. When the parts are in these positions the part 14 is disengaged from 90 the screw 15, so that the rotation of the latter no longer causes the lever 13 and the plate 1 to be displaced. When the plate 1 is pushed back in its guides *z* the lever 35 is rotated back by the spring 37 and engages into 95 the recess 33 in the rod 29 when the latter has been pushed into its lower position by pressure on the knob 32.

During each return movement of the slide *b* the ratchet wheel encounters the inclined 100 surfaces at the upper ends of the teeth 26 and depresses the latter against the pressure of the springs 27, so that the slide *b* is moved over the slide 19 to its original position. From this description it will be seen that 105 during the turning of the wheel *d* the following movements take place simultaneously: 1. Rotation of the knife *c*. 2. Reciprocation of the slide *b* parallelly to the plane of the knife. 3. Intermittent forward movement of the plate 1 in a direction perpendicular to the plane of the knife. 110

What I claim and desire to secure by Letters Patent is:

1. In a meat cutting machine the combination with a revoluble knife of a supporting table, means effecting reciprocation of said table and rotation of said knife, a meat plate slidably mounted on said table, mechanism effecting movement of said plate toward said knife, said mechanism including a ratchet wheel and spring mounted rack teeth co-operating therewith, means whereby the said rack teeth may be adjusted with respect to said ratchet wheel thereby varying the travel 120 of said meat plate, and means whereby said rack teeth may be locked in their adjusted position. 125

2. In a meat cutting machine the combination with a revoluble knife, of a supporting 130

- table, means effecting reciprocation of said table and rotation of said knife, a meat plate slidably mounted on said table, mechanism effecting movement of said plate toward said 5 knife, said mechanism including a ratchet wheel and rack teeth, springs for each of said teeth whereby one tooth may be depressed independent of the remaining teeth.
3. In a meat cutting machine the combination with a revoluble knife, of a sprocket wheel therefor, a counter shaft provided with a sprocket wheel on one end, a chain coöperating with said sprocket wheels, a gear mounted on the opposite end of said counter- 10 shaft, a main driving shaft provided with a gear adapted to mesh with the gear of said countershaft, a radial arm mounted on the gear of said countershaft, a link pivotally connected with said radial arm, a rocking lever pivotally mounted to a stationary part and connected with said link, a supporting table reciprocating in the plane of operation of said knife, a link connected with said rocking lever and said supporting table, a meat 15 plate slidably mounted on said supporting table and operating in a plane angularly to the plane of operation of said supporting table and knife, a threaded shaft carried by said supporting table, a lever pivotally se- 20 cured at one end to said meat plate, said lever having an intermediate threaded portion engaging said threaded shaft, means whereby said lever may be automatically disengaged from said shaft, a ratchet wheel mounted on 25 said shaft, a stationary pawl engaging said ratchet wheel, a rack adjustably mounted, said rack having yieldingly mounted teeth adapted to be engaged by said ratchet wheel, and means whereby said rack may be an- 30 chored in its adjusted position.
4. In a meat cutting machine the combination with a revoluble knife of a sprocket wheel therefor, a countershaft provided with a sprocket wheel on one end, a chain coöper- 35 ating with said sprocket wheels, a gear mounted on the opposite end of said counter- shaft, a main driving shaft provided with a gear adapted to mesh with the gear of said countershaft, a radial arm mounted on the 40 gear of said countershaft, a link pivotally connected with said radial arm, a rocking lever pivotally connected with a stationary part and with said link, a supporting table reciprocating in the plane of operation of 45 said knife, a link connected with said rocking lever and said supporting table, a meat plate slidably mounted on said supporting table and operating in a plane angularly to the plane of operation of said supporting table 50 and knife, a threaded shaft carried by said supporting table, a lever pivotally secured at one end to said meat plate, said lever having an intermediate threaded portion engaging said threaded shaft, a spring actuated plun- 55 ger connected with said threaded lever to normally hold the same out of engagement with said threaded shaft, said plunger having a notch located between its ends, a spring actuated lever carried by said meat plate and having a portion adapted to engage the notch 70 of said plunger, a stationary stop adapted to engage said spring actuated lever to throw the same out of engagement with said plunger, and means effecting rotation of said threaded shaft. 75
5. In a meat cutting machine the combination with a revoluble knife, of a sprocket wheel therefor, a countershaft provided with a sprocket wheel on one end, a chain coöper- 80 ating with said sprocket wheels, a gear mounted on the opposite end of said counter- shaft and provided with a radial arm, a main driving shaft provided with a gear adapted to mesh with the gear of said countershaft, a link pivotally connected with said radial arm, a rocking lever pivotally mounted upon a stationary part and connected with said link, a supporting table reciprocating in the plane of operation of said knife, a link connected 85 with said rocking lever and said supporting table, a meat plate slidably mounted on said supporting table, and operating in a plane angularly to the plane of operation of said supporting table and knife, a threaded shaft carried by said supporting table, a lever piv- 90 tally secured at one end to said meat plate, said lever having an intermediate threaded portion engaging said threaded shaft, a spring actuated plunger connected with said threaded lever normally holding the same 95 out of engagement with said threaded shaft, said plunger having a notch located between its ends, a spring actuated lever carried by said meat plate and having a portion adapted to engage the notch of said plunger, a sta- 100 tionary stop adapted to engage said spring actuated lever and throw the same out of en- gagement with said plunger, a ratchet wheel mounted on said threaded shaft, a stationary pawl engaging said ratchet wheel, a rack ad- 105 justably mounted and having yieldingly mounted teeth adapted to be engaged by said ratchet wheel, and means whereby said rack may be anchored in its adjusted position. 110
6. In a meat cutting machine the combi- 115 nation with a revoluble knife, of a support- ing table reciprocating in the plane of opera- tion of said knife, a main driving shaft, gear- ing mechanism connecting said driving shaft and said revoluble knife, pivotally mounted 120 links connected with said gearing mechanism and supporting table, a threaded shaft car- ried by said supporting table, a meat plate slidably mounted on said table, a threaded lever connected with said meat plate and co- 125 operating with said threaded shaft thereby serving to reciprocate said meat plate, a spring actuated plunger connected with said threaded lever normally holding the same 130 out of engagement with said threaded shaft,

said plunger having a notch located between its ends, a spring actuated lever carried by said meat plate and having a portion adapted to engage the notch of said plunger, a stationary stop adapted to engage said spring actuated lever to throw the same out of engagement with said plunger, and means effecting rotation of said threaded shaft.

7. In a meat cutting machine the combination with a revoluble knife, of a supporting table reciprocating in the plane of operation of said knife, a main driving shaft, gearing mechanism connecting said driving shaft and said revoluble knife, pivotally mounted links connected with said gearing mechanism and supporting table, a threaded shaft carried by said supporting table, a meat plate slidably mounted on said table, a threaded lever connected with said meat plate and operating with said threaded shaft thereby serving to reciprocate said meat plate, a spring actuated plunger connected with said threaded lever normally holding the same out of engagement with said threaded shaft, a plunger having a notch located between its ends, a spring actuated lever carried by said meat plate and having a portion adapted to engage the notch of said plunger, a stationary stop adapted to engage said spring actuated lever to throw the same out of engagement with said plunger, a ratchet wheel mounted on said shaft, a stationary pawl engaging said ratchet wheel, and a rack adjustably mounted and having yieldingly mounted teeth adapted to be engaged by said ratchet wheel thereby effecting rotation of said threaded shaft.

8. In a meat cutting machine the combination with a revoluble knife, of a meat plate slidably mounted on said table and having a meat holder comprising a rigidly mounted member having downwardly projecting teeth and located on one side of said meat plate, a rigidly mounted member located on the opposite side of said meat plate and provided with apertures arranged in vertical alinement, a prong bar adapted to engage the apertures of said last mentioned member, said bar having a movable tooth member adapted to engage the downwardly projecting teeth of said first mentioned member.

9. In a meat cutting machine the combination with a revoluble knife, of a supporting

table, means effecting reciprocation of said table and rotation of said knife, a meat plate 55 slidably mounted on said table, mechanism effecting reciprocation of said plate, a spring actuated plunger carried by said plate having an engaging notch, a spring actuated lever adapted to engage the notch of said 60 plunger, and a stop adapted to engage said spring actuated lever to trip the same and release said plunger thereby interrupting movement of said meat plate.

10. In a meat cutting machine the combination with a revoluble knife, of a supporting table, means effecting reciprocation of said table and rotation of said knife, a meat plate 65 slidably mounted on said supporting table, means effecting reciprocation of said meat 70 plate said means including a threaded shaft revolvably mounted on said supporting table, a ratchet wheel secured on said shaft, a spring pawl or detent engaging said ratchet wheel, a rack adapted to be engaged by said 75 ratchet wheel during the reciprocation of said supporting table thereby serving to rotate said threaded shaft, and means connecting said meat plate with said threaded shaft.

11. In a meat cutting machine the combination with a revoluble knife, of a supporting table, means effecting reciprocation of said 80 meat plate including a threaded shaft revolvably mounted on said supporting table, a lever connected with said meat plate and engaging said threaded shaft, a ratchet wheel secured on said shaft, a spring pawl or detent 85 engaged said ratchet wheel, a rack adapted to be engaged by said ratchet wheel during the reciprocation of said supporting table thereby serving to rotate said shaft, said rack having spring mounted teeth displaceable in 90 the direction of their length, and means whereby said rack may be adjusted to different positions and anchored in its adjusted positions.

In testimony whereof I affix my signature 100 in presence of two witnesses.
